MACHINE FOR PEGGING LIFTS TO SHOE
HEELSErnest O. Aichele and Eugene Aichele,
Hillside, N. J.

Application March 16, 1938, Serial No. 196,142

4 Claims. (Cl. 1-32)

This invention relates to mechanism for pegging lifts to shoe heels.

The invention has for an object to provide a novel mechanism adapted to automatically and

5 simultaneously cut a plurality of metallic pegs from running lengths of wire, thereupon positioning the several cut pegs in properly grouped and spaced relation for insertion through a lift and into a heel body to which the lift is desired to be pegged, and finally driving the pegs home through the lift and into the heel body.

10 The invention has for a further object to provide in an automatic mechanism for the above stated purposes, a novel means for feeding continuous lengths of wire to the peg cutting means in timed relation to the operations of the latter.

15 The invention has for another object to provide an automatically actuated cutting means which functions both to cut the metallic pegs from supplied wire and at the same time to carry the cut pegs into properly grouped and spaced relation for application to a lift and heel body.

20 The invention has for another object to provide a novel driving means to operate upon the entire group of pegs so as to simultaneously drive the same home through the lift and into the shoe heel body; means being provided to actuate the driving means in properly timed relation to the operations of the peg cutting and positioning means.

25 A further object of the invention is to provide means for holding the lift and heel subject to the pegging operations, including an automatic heel clamp having means to actuate the same in timed relation to the peg driving means.

30 Other objects of this invention, not at this time more particularly enumerated, will be understood from the following detailed description of the same.

35 An illustrative embodiment of the novel machine according to this invention is shown in the accompanying drawings, in which—

40 Fig. 1 is a front elevation of the machine; Fig. 2 is a fragmentary vertical longitudinal section thereof, drawn on an enlarged scale; Fig. 3 is a fragmentary horizontal section, taken on line 3—3 in Fig. 2; Fig. 4 is also a fragmentary horizontal section, taken on line 4—4 in Fig. 2; Fig. 5 is a fragmentary vertical longitudinal section, 45 showing a portion of the wire feed actuating mechanism, said section being taken on line 5—5 in Fig. 4; Fig. 6 is a fragmentary transverse vertical section, showing a portion of the heel clamping means, said view being taken on line 6—6 in Fig. 1; and Figs. 7 and 8 are fragmentary longi-

tudinal vertical sectional views, respectively showing successive stages in the operations of the peg cutting and positioning means and the peg driving means.

50 Similar characters of reference are employed in the hereinabove described views, to indicate corresponding parts.

Referring to the drawings, the reference character 10 indicates a base or supporting framework of suitable design, upon the top plate 11 of which is supported, by longitudinally disposed sleepers 12, a bottom deck plate 13, an intermediate deck plate 14 and a top deck plate 15. The several deck plates are supported in suitably spaced superposed relation by corner posts 16. 15

The reference character 17 indicates a longitudinally disposed main shaft. This shaft is journaled at its outer end portion in bearings 18 which are mounted on an extension 19 of the frame-work 10, and the inner end portion of said 20 shaft extends beneath the bottom deck plate 13, said inner end portion thereof being journaled in suitably disposed bearings 20 which are dependent from said bottom deck plate 13. Affixed upon the outer end of said shaft 17 is a pulley 21, or equivalent means, by which the shaft may be driven from any suitable source of power. 25

Journalized in and between said bottom and intermediate deck plates 13 and 14 are suitably disposed and spaced vertical driven shafts 22, the 30 same being arranged to be driven from and by said main shaft 17 by intermediate bevel gears 23 and 24. These driven shafts 22 serve to operate the peg cutting and positioning mechanism.

35 The peg cutting and positioning mechanism comprises opposed longitudinally reciprocable cutter plates 25 which are slidably movable upon the intermediate deck plate 14 in a slideway formed by laterally spaced guide bars 26 and an overlying top plate 27, which are suitably assembled together and affixed to the upper side of said intermediate deck plate 14. Timed reciprocation of each cutter plate 25 is produced by a cooperating actuating cam 28 with which each driven shaft 22 is provided. These cams 28 engage roller studs 29 with which the outer or tail end portion of each cutter plate 25 is provided. Each cutter plate is yieldingly retracted by spring elements 30, whereby the roller studs 29 thereof are retained in operative engagement with the corresponding actuating cams 28. The forward inner end portion of each cutter plate is provided with a group of suitably spaced and disposed vertical passages 31 to receive the wire material from which the pegs are to be cut. Imbedded in the 50

55 Figs. 1 and 2 are fragmentary longitudinal sections, drawn on an enlarged scale; Fig. 3 is a fragmentary horizontal section, taken on line 3—3 in Fig. 2; Fig. 4 is also a fragmentary horizontal section, taken on line 4—4 in Fig. 2; Fig. 5 is a fragmentary vertical longitudinal section, showing a portion of the wire feed actuating mechanism, said section being taken on line 5—5 in Fig. 4; Fig. 6 is a fragmentary transverse vertical section, showing a portion of the heel clamping means, said view being taken on line 6—6 in Fig. 1; and Figs. 7 and 8 are fragmentary longi-

intermediate deck plate 14, beneath each cutter plate 25 are groups of correspondingly spaced and disposed stationary cutter blocks 32 having vertical wire passages 33 with which the passages 31 of the cutter plates align themselves when said cutter plates are retracted to normal initial positions. The cutter plates 25 are made of hardened steel, and the cutter blocks 32 are likewise made of hardened steel, whereby the meeting edges of the respective passages 31—33 thereof will function as wire shearing or cutting edges when the cutter plate passages are forwardly moved across the stationary passages of the cutter blocks.

15 The top plate 27 of the slideway means in which the cutter plates move is provided with groups of correspondingly spaced and disposed vertical peg guiding passages 34 with which the respective groups of cutter plate passages 31 align themselves when said cutter plates 25 are actuated to cut pegs from the wire material fed thereto and thereupon move the cut pegs to positions where in they are subject to the operations of the peg driving means of the machine.

20 25 A wire feeding means is provided to serve each cutter plate 25 of the peg cutting and positioning means. Mounted on the bottom deck plate 13 are laterally spaced standards 35 having bearings 36 in which are journaled the shafts 37 of the respective wire feeding means. Each wire feeding means comprises a feed roll 38 fixed on a shaft 37. Each feed roll is provided with spaced circumferential wire engaging channels 39, which correspond in number to the number of peg cutting and carrying passages 31 with which the cutter plate 25 to be served thereby is provided. Cooperating with each wire engaging channel of the feed roll 38 is a tensioned gripper roller 40. Each gripper roller 40 is mounted on the end of the upwardly extending arm 41 of a pivoted bell-crank lever 42, to the outwardly and oppositely extending arm 43 of which is connected a suitably anchored spring element 44 which yieldably rotates the bell-crank lever 42 to tensionally press said gripper roller toward the feed roll 38.

30 35 40 45 Wire material 45 is led from suitably located and supported supply spools 46 to extend over suitably located and supported guide rollers 47, so that the strands thereof are caused to respectively pass around the feed rolls 38 and between the latter and said cooperating gripper rollers 40. The strands of wire material are engaged by the channels 39 of said feed rolls, and the surfaces of these channels, as well as the surfaces of the gripper rollers 40 are preferably roughened, as by nurling, so that the wire strands will be effectively gripped by and between said feed rolls and gripper rollers so as to be forwardly impelled toward the cutter plates 25 when said feed rolls are moved. From the feed rolls 38, the wire strands respectively extend upwardly to and through the cutter block passages 33, and into the aligned cutter plate passages 31, when the cutter plates 25 are retracted to normal initial position, and the feed rolls 38 are moved to feed the wire strands into such operative relation to said cutter plates 25.

40 45 50 55 60 65 70 75 The means for producing timed operation of the feed rolls 38 in proper relation to the controlled reciprocatory movements of the cutter plates 25, comprises intermeshing gears 48 by which rotation of one shaft 37 is transmitted to the other. Affixed to one of said gears 48 is a ratchet gear 49, and pivoted upon the shaft of such gear 48 is an oscillatable arm 50 upon which

is mounted a spring pressed pawl 51 adapted to operatively engage said ratchet gear 49. Timed oscillation of said arm and pawl is controlled by a cam 52 which is mounted on said main shaft 17. Supported in bearings 53 adjacent to one side of said bottom deck plate 18 is a rock-shaft 54, and affixed to said rock-shaft is a lever member 55 adapted to be operatively engaged by said cam 52. Preferably the cam engaging end portion of said lever member 55 is provided with contact roller 56 to assure an anti-friction engagement of these parts. Also affixed to said rock-shaft 54 is a lever arm 57, the free end portion of which is connected by a link 58 with the free end portion of said oscillatable arm 50. Affixed to said rock-shaft 54 is a crank-arm 59, to which is connected a suitably anchored spring element 60, which yieldably retains the above described transmission means under the control of the actuating arm 52. 20

The means for driving home the pegs into the work, after the same has been cut and positioned by the cutting plates 25, comprises a vertically reciprocable driver plunger 61 which is slidably supported below said intermediate deck 25 plate 14 in a guide casing 62 which is affixed to and supported upon said bottom deck plate 13. The lower end of said driver plunger 61 extends downwardly through the bottom deck plate 13 so as to be operatively engaged by an actuating cam 30 63 which is mounted upon and rotated by said main shaft 17. Preferably the cam engaging end of said driver plunger 61 is provided with a contact roller 64 to assure an anti-friction engagement of these parts. A spring means 65, 35 disposed between the under side of said intermediate deck plate 14 and an axial receiving socket 66 with which the driver plunger is provided, serves to yieldably retain said driver plunger under the control of its actuating cam 63. 40 Affixed to the upper end of said driver plunger 61 are a plurality of up-standing driver rods 67 which correspond in number and position to the number and position of the pegs as cut by the cutter plates 25 and then delivered to positions 45 ready to be driven into the work. The intermediate deck plate 14 is provided with vertical slideways 68 which are aligned with the peg guiding passages 34 with which the top plate 27 of the cutter plate slideway means is provided. 50 The upper free end portions of said driver rods 67 are disposed within and are guided during operation by said slideways 68.

Means are provided for positioning and holding the work upon the top plate 21 and over the peg guiding passages thereof. This means comprises a lift holding plate 69 which is affixed to the top-plate 21. This lift holding plate 69 is provided with an opening 70 shaped to conform substantially to the peripheral shape of a heel lift 71, thus providing a receiving socket within which the latter may be deposited and by which it may be held in proper position to receive insertion therethrough of the groups of cut pegs by which the same is to be pegged to an overlying heel body 72, when the latter is applied over and registered with said lift. 55 60 65

Means are provided for automatically clamping a heel body 72 upon the deposited lift 71 which is desired to be pegged thereto. This clamping means comprises a vertically reciprocable clamp plunger 73 which extends slidably through the top deck plate 15 in alignment with the lift socket of the lift holding plate 69. The means for producing properly timed operation of said clamp 75

plunger 73 comprises a longitudinal rock-shaft 74 journaled in bearings 75 mounted upon the top deck plate 15. Affixed on said rock-shaft 74 is a clamp plunger actuating cam 76 to operatively engage the upper end of said clamp plunger 73. Preferably said upper end of said clamp plunger 73 is provided with a contact roller 77 to assure an anti-friction engagement thereof by said actuating cam 76. Suitably connected with said clamp plunger 73 are suitably anchored spring elements 78 which yieldably retain the clamp plunger 73 under the control of said actuating cam 76. Mounted on the main shaft 17 is operating cam 19 which serves to produce and properly time the oscillations of said rock-shaft 74 and clamp plunger actuating cam 76. Pivots connected with the frame-work extension 18 is a lever member 80, which underlies and is operatively engaged by said operating cam 19. Preferably said lever member 80 is provided with a suitably mounted and located contact roller 81 to assure an anti-friction engagement thereof by said operating cam 19. Suitably anchored spring means 82 is connected with said lever member 80 to yieldably retain the same under the control of said operating cam 19. Affixed to the rock-shaft 74 is a lever arm 83, and interconnected between said lever member 80 and lever arm 83 is a spring compensated link rod means. This link rod means comprises a lower link rod section 84 pivotally connected by its lower end to said lever member 80 and having in affixed relation to its upper end a cylinder member 85. Pivotally connected by its upper end to said lever arm 83 is an upper link rod section 86 having at its lower end a piston head 87 slidably engaged in said cylinder member 85; said rod section slidably extending through the upper end cap 88 of said cylinder member 85. Engaged around said upper link rod section 86, between the piston head 87 thereof and the upper end cap 88 of the cylinder member 85, is a compression spring 89.

In the operation of the machine, a lift 71 is deposited within the holding plate 69, whereupon a heel body 72 to which the lift is to be pegged is superimposed upon the lift 71 in properly aligned relation between the same and the raised clamp plunger 73. While the cutter plates 25 occupy retracted positions, in which their wire passages 31 are aligned with the passages 33 of the cutter blocks 32 (as shown in Fig. 2), the wire feeding means, by the timed operation thereof as controlled by the cam 52, is operated to effect a rotative movement of the feed rolls 38 which advances the upper end portions of the wire strands 45 upwardly through the cutter block passages 33 and into cutter plate passages 31 until stopped by engagement with the under side of the slideway top plate 27. Rotation of the cutter plate actuating cams 28 operates to advance or move inwardly the cutter plates 25. Such movement of the cutter plates shears away the end portions of the wire strands engaged in the passages 31 thereof, thus producing the pegs 90 by which the lift 71 is to be pegged to the heel body 72. The inward movement of the cutter plates carries the cut pegs 90 into alignment with the peg guiding passages 34 of the slideway top plate 27, thus positioning the pegs beneath the lift 71 in the desired grouped and spaced relation as predetermined by the number and grouping of said cutter plate and top plate wire passages. When the pegs 90 are thus moved into position ready to be simultaneously driven through the lift 71 and into the heel body 72, said pegs will also be aligned with the

ends of the corresponding grouped and guided driver rods 67 of the driver plunger 61, which, while the pegs are moved into position, remains downwardly retracted (see Fig. 7).

In the meantime, the clamp plunger 73, under the timing control of the actuating cam 19 and intermediate operating mechanism, is caused to descend and thereby engage the heel body 72 so as to firmly hold the same against displacement, and also properly backed to withstand the thrust of the pegs 90 when the latter are subsequently driven thereinto. Owing to the spring compensated link rod structure which connects the cam actuated lever 80 with the rock-shaft lever 83, the clamp plunger 73 and its operating mechanism will not only automatically adjust itself to different heights of heel bodies, but the compression of said spring 89, due to the excess throw of the lever 80, as compared with the maximum movement required of the rod-shaft lever 83 to effect maximum throw of the clamp plunger actuating cam 76, will exert a strong tensional pressure upon the latter parts, which will be in excess of resistance of the lift and heel body to the penetration thereof by the pegs 90, when the latter are driven home, and consequently the heel body will be firmly and strongly backed against yielding to the thrust of the entering pegs.

The cams 28 which control the movements of the cutter plates 25 are so shaped as to cause the latter to dwell in their inwardly moved positions during the peg driving operations, and until after completion of said operations and retraction of the driver rods 67.

The cam 63 which controls the operation of the driver plunger 61 is so shaped as to properly time the rise and fall of said driver plunger relative to the operation and dwell of the cutter plates 25. While, therefore, the cutter plates 25 dwell in their inwardly moved positions whereby the pegs 90 are held aligned between the guiding passages 34 and the driver rods 67, said cam 63 operates to raise the driver plunger 61. The upward movement of the driver plunger slides upwardly the driver rods 67 which engage the lower ends 45 of the pegs 90, and consequently the upward movement of the driver rods 67, in turn drive upwardly said pegs 90, thereby causing the latter to pierce the lift 71 and penetrate the shoe heel 72, so that all the pegs are simultaneously driven 50 home in a single stroke (see Fig. 8). After the pegs are thus operatively applied to the lift and heel body, the cam 63 permits the driver plunger and its driver rods to return to normal initial lowered position, whereupon the cams 28 return 55 the cutter plates 25 to normal initial positions, following which the wire feeding means operates to again advance the wire strands into the cutter plate passages 31, and the above described cycle of operations may be repeated.

It will be understood that the machine driving transmission may include any suitable trip clutch mechanism (not shown) whereby the main shaft 17 is automatically stopped upon completion of one revolution.

As many changes could be made in the above described embodiment of our invention, and many apparently widely different embodiments of the same could be made without departing from the scope thereof as defined by the following claims, 70 it is intended that all matter contained in the above description or shown in the accompanying drawings shall be interpreted as illustrative and not in a limiting sense.

We claim:

1. In a machine of the kind described, a stationary plate, a pair of opposed reciprocable cutter plates slidably mounted on said stationary plate, each cutter plate having groups of suitably spaced wire receiving passages extending vertically therethrough, said stationary plate having corresponding groups of wire receiving passages extending vertically therethrough with which said respective groups of cutter plate wire passages register when said cutter plates are retracted to normal initial positions, driven cam means for actuating said cutter plates, wire feeding rolls and cooperating tensioned gripper rollers for delivering a plurality of wires from which pegs are to be cut upwardly through said stationary plate passages and into said cutter-plate passages, means for intermittently actuating said wire feeding rolls in timed relation to the operations of said cutter plates, a lift supporting plate above said cutter plates, said lift supporting plates having groups of peg guiding passages with which the wire receiving passages of said cutter plates register upon completion of peg cutting movements of said cutter plates, means on said lift supporting plate to position a lift over the peg guiding passages thereof, means to hold a heel body superimposed upon said lift, a vertically reciprocable driver plunger beneath said stationary plate, said plunger having a plurality of upstanding plunger rods corresponding in number and grouping to the number and grouping of said peg guiding passages of the lift supporting plate and being aligned therewith, said stationary plate having corresponding plunger rod guide passages, and cam means for actuating said driver plunger in timed relation to the peg cutting and positioning movements of said cutter plates.
2. In a machine of the kind described as defined in claim 1, wherein the means for holding the heel body operatively related to a deposited lift and in resistance to the thrust of pegs thereinto includes a self-adjusting clamp means, means for actuating said clamp means, and a driven timing cam for controlling the clamp actuating means.
3. In a machine of the kind described, a stationary plate, a pair of opposed reciprocated cutter plates slidably mounted on said stationary plate, each cutter plate and said stationary plate having a plurality of alignable peg wire receiving openings, means for supplying wire to said receiving openings in timed relation to the operation of said cutter plates, a lift supporting means above said cutter plates having a plurality of peg guiding passages with which the openings of said cutter plates are aligned upon completion of peg cutting movements of said cutter plates, means to hold a heel body superimposed upon said lift, a peg driver means including driving means for each cut peg whereby all pegs are simultaneously driven into said lift and heel, and means to actuate said cutter plates and peg driver means in timed relation.
4. In a machine of the kind described as defined in claim 3, wherein the means for holding the heel body operatively related to a deposited lift and in resistance to the thrust of pegs therein-
to includes a self-adjusting clamp means, means for actuating said clamp means, and a driven timing cam for controlling the clamp actuating means.

ERNEST O. AICHELE. 35
EUGENE AICHELE.
